UNITED STATES PATENT OFFICE

WILLIAM C. HIERING, OF NEWARK, NEW JERSEY, ASSIGNOR TO J. E. MERGOTT CO., OF NEWARK, NEW JERSEY, A CORPORATION OF DELAWARE

ATTACHMENT FOR HOLDING CIGARETTE CASES

Application filed March 22, 1930. Serial No. 438,115.

This invention pertains to a cigarette case holding device which may be attached to the instrument board of an automobile.

While driving an automobile, motorists find it inconvenient and hazardous to search in the pockets of their clothing for cigarettes, and it is an object of this invention to provide a device which may be attached to the instrument board of an automobile to hold 10 cigarettes in their original paper cartons or in cigarette package holding cases within convenient reach of the occupants of the automobile.

A further object is the provision of a cigarette case holding attachment which may be resiliently maintained in several positions to suit the convenience of the user.

These and other advantageous objects, which will later appear, are accomplished by the simple and practical construction and arrangement of parts hereinafter described and exhibited in the accompanying drawing, forming part hereof, and in which:

Figure 1 represents an elevational view of 25 the device attached to the instrument board of an automobile.

Figure 2 represents a sectional elevational view of the attachment rotated to a position transverse to that shown in Figure 1.

Figure 3 represents a partial plan view of 30 the device.

Figure 4 represents a perspective view of a spring used in the device.

Referring to the drawing, a U-shaped 35 clamp member 5 having legs 6 and 7, is attached to the instrument board 9 of an automobile by the clamping action of a bolt 8 in threaded engagement with the leg 6.

Fixed to the leg 7 is a U-shaped bracket 10, 40 the legs of which are pivotally connected by means of pins 17 to the arms 11, the latter projecting laterally from the upstanding end walls of an open casing 12 having a retaining flange 13.

Interposed between an end wall of casing 45

12 and the extremities 16 of the legs of bracket 10 is a bowed spring 14, provided with prongs 15 embracing the arms 11.

In operation, it will be seen that the above structure enables the casing 12 to be resiliently maintained in either of three positions, viz: one position perpendicular to the instrument board, as shown in Figure 1, and two positions parallel with the instrument board, as shown in Figure 2, the movement of the casing to the last mentioned positions being limited by the portions 18 of the bracket legs. 50

In one position, the spring engages the legs of bracket 10, and in the other position, the spring engages the side edges of the legs, 55 the spring moving at all times with the arms 11.

The casing is designed to hold a cigarette package holding case 19 of a well known type, and the case is securely held and prevented 60 from rattling by a spring 20 struck out from an end wall of the casing. 65

From the above description it will be seen that I have provided a simple and convenient attachment for carrying cigarette package holders on the instrument board of an automobile, or any other suitable support. 70

The foregoing disclosure is to be regarded as descriptive and illustrative only, and not as restrictive or limitative of the invention, 75 of which obviously an embodiment may be constructed including many modifications without departing from the general scope herein indicated and denoted in the appended claims. 80

Having thus described my invention, what I claim as new and desire to secure by Letters Patent, is:

1. A device for supporting a cigarette case on the instrument board of an automobile, 85 comprising a bracket having laterally projecting legs, a casing having laterally projecting arms pivotally connected with the legs, resilient means interposed between the extremities of the legs and a wall of the cas- 90

ing to maintain the casing in adjusted positions, and means to attach the bracket to the instrument board.

2. A supporting device, comprising a bracket having laterally projecting legs, a casing having laterally projecting arms pivotally connected with said legs, a bowed spring mounted on the arms and interposed between the extremities of the legs and the casing, said spring embracing said arms, and clamping means connected with the bracket.

This specification signed this 20th day of March, 1930.

WILLIAM C. HIERING.
